(57) **CLAIM**

The ornamental design for a LED skin treatment device set, as shown and described.

DESCRIPTION

FIG. 1 is a top perspective view of a LED skin treatment device set, showing my new design;

FIG. 2 is an exploded perspective view thereof;

FIG. 3 is an exploded front elevational view thereof;

FIG. 4 is an exploded rear elevational view thereof;

FIG. 5 is an exploded right-side elevational view thereof, the left-side elevational view being a mirror image thereof;

FIG. 6 is an exploded top plan view thereof;

FIG. 7 is an exploded bottom plan view thereof; and

FIG. 8 is a bottom perspective view thereof; and,

FIG. 9 is a cross-sectional view taken in the direction of line 9-9 shown in FIG. 3.

The broken lines in the figures depict portions of the LED skin treatment device set that form no part of the claimed design.

1 Claim, 8 Drawing Sheets
